UNITED STATES PATENT OFFICE.

THOMAS P. MARTIN, JR., OF OKLAHOMA, OKLAHOMA.

CURRENCY-WRAPPER.

1,162,501.

Specification of Letters Patent. Patented Nov. 30, 1915.

Application filed June 8, 1915. Serial No. 32,878.

To all whom it may concern:

Be it known that I, THOMAS P. MARTIN, Jr., a citizen of the United States, and a resident of Oklahoma city, in the county of Oklahoma and State of Oklahoma, have invented certain new and useful Improvements in Currency-Wrappers, of which the following is a specification.

The main object of my invention is to provide a wrapper for currency which, owing to the manner in which it is creased or scored, may be folded to form a wrapper for various sized packages, and which may be quickly and positively secured in position, so as to form a neat and compact package suitable for shipment through the mails.

With these and other objects in view, which shall become apparent as the description proceeds, my invention resides in the construction, combination, and arrangement of parts to be hereinafter described and claimed, and illustrated in the accompanying drawings forming a part of this specification, in which like reference characters indicate like parts.

Figure 1 is a perspective view of my wrapper folded to accommodate a large package. Fig. 2 is a perspective view of the wrapper folded to receive a smaller package. Fig. 3 is an enlarged transverse vertical section taken on the line 3-3 of Fig. 1. Fig. 4 is an enlarged section taken on the line 4-4 of Fig. 2. Fig. 5 is a longitudinal section on the line 5-5 of Fig. 2. Fig. 6 is a longitudinal vertical section of my wrapper with the ends folded in a different manner. Fig. 7 is a plan view of one form of wrapper blank. Fig. 8 is a perspective view showing a modified form of wrapper having means for securely fastening it about a package. Fig. 9 is a perspective view of a wrapper showing a further modification.

Referring to the form shown in Figs. 1 to 7, inclusive, the wrapper is formed from a rectangular piece of cardboard or other suitable material A, which is scored along the lines 3 to form a bottom section 1, a series of relatively narrow side and top sections 2, and an outside section 5. The bottom, side, and top sections have a flap at either end, the flaps 6 upon the bottom section being relatively longer than the flaps 4 on the narrow sections. The flaps 6 are scored transversely near their centers along parallel lines 7. When it is desired to wrap a large package, the wrapper blank is creased along the

scored lines at either side of the bottom section, and along alternate lines thereafter. The wrapper is then folded about the package as shown in Fig. 1, and the flaps 4 60 folded inward and the flaps 6 bent upward to form ends for the wrapper. If it is desired to wrap a smaller package, the blank is creased along all the scored lines 3, and the wrapper folded about the package as 65 shown in Fig. 2, the flaps 4 being bent over the end of the package and the flaps 6 then bent upward and over the top of the wrapper and secured by a suitable fastener as shown in Fig. 2, or the flaps 6 may first be 70 bent over the end of the package and the flaps 4 then bent down as shown in Fig. 6. By scoring the flaps 6 at several places as 75 shown at 7, the blank may be conveniently folded to fit packages varying slightly in size. It will be apparent that the blank could be formed of a greater number of sections or of narrower sections, if desired, so as to make a larger or smaller package. The 80 form of wrapper which I have just described is to be used with an outside wrapper of strong manila paper, upon which is written the amount of money, name of the sender, to whom sent, etc., and finally sealed at the proper places, as is the custom in 85 making shipments of currency in the ordinary paper package.

With the form of wrapper shown in Fig. 8, no outside wrapper is used, the flaps 6' 90 on the bottom section being elongated to form fastening strips 8 and 9, one of which is slotted as shown at 10. In using this wrapper the flaps 6' are folded over the ends of the package and the strip 9 is then passed through the slot 10 and bent back on 95 itself as shown in dotted lines. The strips are secured in this position by sealing wax, which is also applied at the points 11 where the flaps are cut away so that all parts of the wrapper may be securely sealed.

In Fig. 9 I have shown a wrapper of this same type but having curved cut away portions 11' for the sealing wax instead of the V shaped notches 11 in which the fastening strips are secured by head and socket fastenings 12 and 13.

It will thus be seen that I have provided a wrapper blank capable of being folded to fit various size packages of currency, which may either be used with an outside wrapping of paper, or used as a self fastening wrapper.

I claim:—

1. A wrapper comprising a bottom section, a series of parallel and relatively narrow side and top sections, end flaps upon the said narrow sections of a length equal to the width of the said narrow sections, longer end flaps upon the bottom section scored transversely at several points approximately on a line with the ends of the short end flaps, and having elongated fastening strips formed integral therewith, cutaway portions in the sides of the last mentioned end flaps, and fastening members upon the said fastening strips.
2. A wrapper comprising a bottom section and a series of parallel and relatively narrower side and top sections of equal width adapted to be folded to form a receptacle the sides of which consist of either one or a plurality of the said narrow sections, end flaps upon the narrow sections, and longer end flaps upon the bottom section.
3. A wrapper comprising a bottom section and a series of parallel and relatively narrower side and top sections adapted to be folded to form a receptacle the sides of which consist of either one or a plurality of the said narrow sections, and end flaps upon the bottom section scored transversely at several points on lines a distance from the bottom section equal to the width of one or more of the above mentioned narrow sections.
4. A wrapper comprising a bottom section and a series of parallel and relatively narrower side and top sections adapted to be folded to form a receptacle the sides of which consist of either one or a plurality of the said narrow sections, elongated tapering end flaps upon the bottom section having cut away portions in the sides thereof one of the last mentioned end flaps having a transverse slot near its end adapted to be engaged by the other end flap.

the said narrow sections, elongated tapering end flaps upon the bottom section, one of the 40 said end flaps having a transverse slot formed near its end adapted to be engaged by the other end flap.

5. A wrapper comprising a bottom section and a series of parallel and relatively narrower side and top sections adapted to be folded to form a receptacle the sides of which consist of either one or a plurality of the 45 said narrow sections, elongated end flaps upon the bottom section having notches 50 cut in the sides thereof and fastening members on the said end flaps.

6. A wrapper blank scored transversely to form a plurality of substantially oblong sections having end flaps thereon and adapted 55 to be folded along the scored lines to form receptacles having sides formed of one or more of the said sections.

7. A wrapper comprising a bottom section and a series of parallel and relatively narrower side and top sections adapted to be folded to form a receptacle the sides of 60 which consist of either one or a plurality of the said narrow sections, elongated end flaps upon its bottom section and fastening members 65 upon the said elongated end flaps.

8. A wrapper comprising a bottom section, a series of parallel and relatively narrow side and top sections, end flaps upon the said narrow sections, elongated tapering 70 end flaps upon the bottom section having cut away portions in the sides thereof one of the last mentioned end flaps having a transverse slot near its end adapted to be engaged by the other end flap.

THOMAS P. MARTIN, JR.
